UNITED STATES PATENT OFFICE.

JOHN ROESSER, OF BALTIMORE, MARYLAND, ASSIGNOR, BY DIRECT AND MESNE ASSIGNMENTS, TO THE NATIONAL SMOKE CLEANSING COMPANY, A CORPORATION OF DELAWARE.

SMOKE-CLEANER AND CINDER-CATCHER AS APPLIED TO LOCOMOTIVES.

No. 846,052.

Specification of Letters Patent.

Patented March 5, 1907.

Application filed March 14, 1906. Serial No. 305,353.

To all whom it may concern:

Be it known that I, JOHN ROESSER, a citizen of the United States, residing at Baltimore city, State of Maryland, have invented 5 certain new and useful Improvements in Smoke-Cleaners and Cinder-Catchers as Applied to Locomotives, of which the following is a specification.

My invention relates to an improvement 10 in a smoke-cleaning and cinder-catching device as applied to locomotives, the primary object being, as the name implies, to cleanse the smoke and to a great extent separate therefrom the heavy carbon and cinders before being discharged through the stack, 15 thereby greatly reducing the possibility of causing fires by reason of the hot cinders or sparks being emitted from the stack of a locomotive and also to a great extent abating 20 the nuisance of smoke.

I have sought in this invention to provide a simple and cheap device and one which may be readily applied to a horizontal boiler of a locomotive.

25 With these objects in view my invention consists in certain novel features of construction and combinations of parts, which will be hereinafter described, and pointed out in the claims.

30 The accompanying drawing is a longitudinal sectional view of my invention with parts shown in elevation.

A represents a horizontal boiler of a locomotive, and B is a smoke-chamber divided 35 into the compartments 1 and 2 by the partition 3, the said partition depending from the top of the smoke-chamber B and projecting vertically until within a short distance of the bottom of the compartment 40 2, when it assumes an L shape and projects within the compartment 2. To the left and just below the bent L of the partition and bent in conformity therewith is another partition 4, which extends from the bed of the 45 boiler-carrying frame at 5 within the compartment 1 to a point 6 within the compartment 2, where the L of the partition 3 terminates, (designated by 7,) thereby forming an opening 8 between the compartments 1 50 and 2 of the smoke-chamber B. Within the compartment 1 of the smoke-chamber B is extended the steam-pipe 9 in the upper part thereof, and by means of an L connection 10

it is then extended downward at a point directly above the opening 8, which extends 55 within the compartment 1. This pipe is connected directly with the boiler of the engine at any point and by any suitable means (not shown) and is provided with a valve (not shown) for controlling the discharge of 60 the steam and is for the purpose of conveying and discharging live steam within the compartment 1 of the chamber B for the purpose which will be hereinafter described.

11 is a steam-pipe connected by any suitable means (not shown) with the cylinder C and is extended within the compartment 1 of the chamber B and thence by means of the L connection 12 is extended across the compartment 1 and by means of a hole 13, cut 70 through the partition 3, is extended within the compartment 2 and by means of another L connection 14 is extended upward within the compartment 2 at a point within a short distance from the top of said compartment and directly beneath the opening (not shown) of the stack 15. This pipe is for 75 the purpose of conveying the exhaust-steam from the cylinder C and discharging it within the compartment 2 of the chamber B for 80 the purpose hereinafter described.

The smoke-chamber and the partitions therein are made of any suitable material, but preferably of boiler-iron or similar material used in the construction of boilers and 85 engines.

My device is operative as follows: The smoke as it passes from the fire-box of the locomotive passes through the tubes or flues 16 in the boiler A and thence into the compartment 1 of the smoke-chamber B. By 90 means of discharging steam into the compartment through the pipe 9 the smoke is directed downward through the opening 8, formed by the partitions 3 and 4, which 95 might be termed a "pipe" or "flue," and into the compartment 2 of the chamber B. The action of the steam on the smoke as it passes downward through the opening 8 is to wash out the carbon and other visible matter, and 100 after the smoke enters the compartment 2 it is again acted upon by the exhaust-steam being discharged through the pipe 11 and again washed, and the carbon and other visible matter is to a great extent precipitated into 105 the bottom of the chamber B, from whence it

can be removed through the doors 17, an overflow-pipe 18 being provided and located a suitable distance above the bottom of the chamber for draining off the excess of water which may form in the chamber by reason of condensing the steam therein. It will thus be seen by the use of my device the heavy carbon and visible matter in the smoke will be for the most part washed out and precipitated down into the bottom of the chamber, while the gases will pass out the stack, and by the discharge of the exhaust-steam through the pipe 11, which is located directly below the opening of the stack, (not shown,) the draft is not interfered with, but, on the contrary, is to some extent increased.

It is evident that slight changes might be resorted to in the form and arrangements of the several parts described without departing from the spirit and scope of my invention, and hence I do not desire to limit myself to the exact construction as herein set forth; but,

Having fully described my invention, what I claim, and desire to secure by Letters Patent, is—

1. The combination of a locomotive substantially as hereinbefore described comprising a boiler and a smoke-chamber, of a partition separating the chamber into two compartments and forming a flue connecting the compartments so formed, whereby the smoke upon entering the first compartment is retained therein for the purpose of being acted upon by the live steam from the jet therein contained, of a steam-pipe leading from the boiler and provided on the free end thereof with said jet and discharging live steam into the first compartment for the purpose of partially washing out the carbon and other visible matter in the smoke, and for directing the smoke through the flue so formed by the partition and into the second compartment, of an exhaust-steam pipe connecting with the cylinders on the locomotive and provided with a jet on the free end thereof and discharging within the second compartment and above the point where the flue enters thereinto for the purpose of washing out the heavy carbon and other visible matter in the smoke and

whereby they are precipitated into the bottom of the compartment, of a stack on the top of the chamber and opening within the second compartment through which the gases are emitted, being so directed by the steam-jet therein contained for the purpose as herein set forth.

2. The combination of a locomotive substantially as hereinbefore described, comprising a smoke-chamber, of a partition separating the chamber into two compartments and forming a flue connecting the compartments so formed whereby the smoke upon entering the first compartment is temporarily retained therein for the purpose of being acted upon by the live steam from the jet therein contained, of a steam-pipe leading from the boiler and provided on the free end thereof with said jet and discharging live steam into the first compartment for the purpose of partially washing out the carbon and other visible matter in the smoke and for directing the smoke through the flue so formed by the partition and into the second compartment, of an exhaust-steam pipe connected with the cylinders on the locomotive and provided with a jet on the free end thereof and discharging within the second compartment and above the point where the flue enters thereinto for the purpose of washing out the heavy carbon and other visible matter in the smoke and whereby the carbon and other visible matter is precipitated into the bottom of the compartment of a stack on the top of the chamber and opening within the second compartment through which the gases are emitted, of an outlet-pipe located a sufficient distance above the bottom of the first compartment for draining off the excess of water formed by the condensing of the steam therein, of doors located in the side near the bottom of the second compartment through which the debris may be removed for the purpose as herein set forth.

In testimony whereof I affix my signature in presence of two witnesses.

JOHN ROESSER.
